ART OF FORMING ASSEMBLIES

George F. Linquist, Seattle, Wash., assignor to
 I. F. Laucks, Inc., Seattle, Wash., a corporation
 of Washington

Application July 2, 1935, Serial No. 29,460

5 Claims. (Cl. 144—309)

This invention relates to the art of forming assemblies in bundles, and more particularly to methods of forming box-sides and similar articles.

5 An object of the invention is the provision of a procedure whereby glued assemblies, such for instance as box-sides, i. e. articles whereby the top, bottom, side or other walls of a box may be formed, or similar constructions may be held under pressure for the setting of the glue and made ready for shipment in groups.

10 More specifically, it is an object of the invention to avoid the time-consuming and expensive operations which have been utilized up to the present time for the formation of assemblies of the character under consideration and in making them ready for shipment.

15 Other objects of the invention will in part be obvious and will in part appear hereinafter.

20 The invention accordingly comprises the several steps and the relation and order of one or more of such steps with respect to each of the others thereof, which will be exemplified in the method hereinafter disclosed, and the scope of the application of which will be indicated in the claims.

25 For a fuller understanding of the nature and objects of the invention, reference should be had to the following detailed description taken in connection with the accompanying drawing, in

30 which:

Figure 1 is a perspective view of a box-side assembly bundle such as may be produced in accordance with one embodiment of the invention; and

35 Figs. 2, 3 and 4 are perspective views in part diagrammatic and having parts broken away such as may be produced with other embodiments of the invention.

40 In the manufacture of glued box-sides and the like, it has been customary to assemble two or more slats side by side with a cross cleat at each end glued to the slats and holding them in proper relative position. These have ordinarily been gathered in groups and bound between screw clamps or in complicated and expensive machines until the glue was set; and usually for convenience tied loosely across the middle with a string so that the various assemblies could be handled as a bundle. This time-consuming, cumbersome and otherwise objectionable practice, recognized as undesirable, but nevertheless deemed unavoidable, necessitated multiplication of equipment and compelled long waits before the product was ready for shipment or storage and until the equipment could be used again, since in all cases

the work was kept in apparatus the full time required for the glue to set. The present invention departs sharply from such unsatisfactory procedure and makes for greatly increased simplicity and efficiency. It contemplates a method of making box-side assembly bundles ready, at the instant of completion of the bundle, for immediate shipment or storage without waiting for the glue to set. In the performance of the single step of forming an immediately available 10 bundle of box-side assemblies, the method, at the same time and without further equipment than that used in the bundling, provides and maintains the condition requisite to the proper setting of the glue and proper completion of the 15 box-sides.

Individual box-side assemblies are produced in the ordinary way by applying glue at the ends of the slats 1 or to the face of the corresponding cleats 2, as may be the more convenient. After 20 being glued, these assemblies to the number of say twenty-four or twenty-five, are then stacked by hand, or by machine, with the cross cleats at each end aligned in sets, as best shown in Fig. 1. The two exterior assemblies, on the top and on the bottom in the said figure, have their cleats on the outside, thus protecting the more delicate slats. Before the glue has set, the assemblies are then, according to the invention, bound closely into a bundle, with the cleats in close contact with their 30 respective slats, by tightly applying ties 3 (3' in Fig. 4) over the cleats, as indicated in all of the figures, and securing them firmly against slipping or release, as indicated at 4 (5' in Fig. 4). The collecting, arranging, tie-applying and securing procedures need not be sharply isolated or 35 distinct steps but may go on to some extent at the same time or merge into each other. Much the best and most effective ties are flat steel straps of known construction not necessary to 40 illustrate in detail. Wire or rope may be used, but to less advantage than the flat steel straps. Where wire is chosen protective pieces should be interposed between the end edges of the cleats and the wire to avoid cutting into the cleats 45 unduly. Rope has the defect for this use of being subject to stretching. In Fig. 1, the box-side assemblies after being glued and stacked have been bound closely into a bundle with the cleats in close contact with their respective slats by 50 tightly applying to each end set of cleats the steel strap 3 running lengthwise of the cleats approximately axially thereof and enclosing the set, and firmly securing each strap, one end of which is run through, or lapped with, the other and 55

clinched, or otherwise fixed at 4 against return movement, thus tying the parts tightly and permanently together in the correct relative position and under the pressure required to insure the proper setting of the glue. This provides a neat package with a moderate amount of strapping and with adequate distribution of pressure on the glue line. Greater rigidity and greater uniformity of pressure is obtained by the location of the cleats of the two exterior assemblies on the outside, as indicated above.

The method which resulted in the bundle of Fig. 2 is the same as that already described in the gluing and stacking of the assemblies, but the ties, steel straps 3 being shown, are passed crosswise of the cleats and lengthwise of the slats around the entire bundle. These are drawn tightly and have their ends fastened securely as in Fig. 1. Two straps symmetrically arranged are effective and sufficient, but one will serve where the bundle is narrow. As will be evident the crosswise straps exert a crosswise component tending to slide each outside cleat inward on the slats out of its proper position if the two exterior assemblies are freshly glued. It is best, therefore, to insure the fixity of these cleats, as may be done by selecting these particular assemblies from previously glued box-sides wherein the glue has set. This manner of application gives good distribution of pressure by greater length of strapping.

The method which produced the bundle of Fig. 3 differs from either of these already described in utilizing aligned spaces between slats which form slots adjacent to each end set of cleats which can thus be completely encircled and so bound together by short straps or ties 3 tightly drawn and firmly secured at 4. In this way the cleats are placed and held in close contact with their slats and the glue sets during shipment or storage as in all the other forms of the method. Two symmetrical straps are best and sufficient.

The bundle shown in Fig. 4 is bound and held by short steel straps 3' having inturned ends 4' held fast by tangs 5' punched into the respective outer cleats. The straps having been tightly drawn, the tangs serve to maintain the bundle in tightly drawn relationship, so as to assure that the glue will set under proper conditions and that the bundle may be handled as for shipment or storage as soon as the straps are in place. The straps extending over the ends of the cleats, as exemplified at the right of Fig. 4, serve to prevent lateral slipping of the cleats and the straps extending over the edges of the cleats, as exemplified at the left of Fig. 4, serve to bind the bundle firmly at more or less spaced portions along its edge. As many straps as desired may be used at each end of the bundle, or at such other points as cleats or other smaller surface members are provided. The method is essentially as described in connection with the other figures.

It will be apparent that the method as exemplified above eliminates, as a separate step, one complete operation for the performance of which existing plants have provided expensive and complicated equipment, and, by combining it with, and making it incidental to, the tying of the box-side assemblies into a bundle immediately available for shipment or storage, saves time, space, labor and the substantial cost of presses or other equipment heretofore used.

As will be apparent, the invention in its broader

aspects, is adapted for use in a variety of cases where assemblies of small-surface members with large-surface members are to be formed by gluing and grouped in bundles.

Since certain changes may be made in carrying out the above method without departing from the scope of the invention, it is intended that all matter contained in the above description shall be interpreted as illustrative and not in a limiting sense.

The invention claimed is:

1. The method of making composite box sides and the like and bundling the same; which comprises providing a plurality of assemblies each formed by gluing cross cleats to each end of the face of body-forming means; stacking such assemblies, with the cleats at the ends thereof aligned in sets; and, before the glue has set, binding the stacked assemblies into a bundle with the cleats in close contact with the body material by tightly applying tie-means to the portions of the stack containing the aligned cleats, and firmly securing the tie-means to hold the members of each assembly tightly together during the setting of the glue and at the same time to bind the associated assemblies in a bundle for handling or shipment.

2. The method of making composite box sides and the like and bundling the same; which comprises providing a plurality of assemblies each formed by gluing cross cleats to each end of the face of body-forming means; stacking such assemblies, with the cleats at the ends thereof aligned in sets, and with the cleats on the exterior assemblies disposed at the outside thereof; and, before the glue has set, binding the stacked assemblies into a bundle with the cleats in close contact with the body material by tightly applying tie-means to the portions of the stack containing the aligned cleats to draw the exterior cleats toward each other, and firmly securing the tie-means to hold the members of each assembly tightly together during the setting of the glue and at the same time to bind the associated assemblies in a bundle for handling or shipment.

3. The method of making composite box sides and the like and bundling the same; which comprises providing a plurality of assemblies each formed by gluing cross cleats to each end of the face of body-forming means; stacking such assemblies, with the cleats at the ends thereof aligned in sets, and with the cleats on the exterior assemblies disposed at the outside thereof; and, before the glue has set, binding the stacked assemblies into a bundle with the cleats in close contact with the body material by tightly applying to each end-set of cleats a tie running lengthwise of the outside cleats and enclosing the set to draw the exterior cleats toward each other, and firmly securing the tie-means to hold the members of each assembly tightly together during the setting of the glue and at the same time to bind the associated assemblies in a bundle for handling or shipment.

4. The method of making composite box sides and the like and bundling the same; which comprises providing a plurality of assemblies each formed by gluing cross cleats to each end of the face of body-forming means; stacking such assemblies, with the cleats at the ends thereof aligned in sets, together with two exterior assemblies each having end cleats on the outside and insured against slipping; and, before the glue on

- the first-mentioned assemblies has set, binding the stacked assemblies closely together into a bundle by tightly applying spaced tie-means crosswise of both cleat sets and around the bundle, and firmly securing the tie-means to hold the members of each assembly tightly together during the setting of the glue and at the same time to bind the associated assemblies in a bundle for handling or shipment.
- 5 5. The method of making composite box sides and the like and bundling the same; which comprises providing a plurality of assemblies each formed by gluing cross cleats to each end of the face of body-forming means, said body-forming means comprising at least three spaced slats;
- stacking such assemblies with the cleats at the ends thereof aligned in sets and the two exterior assemblies having their cleats on the outside, each of at least two sets of the spaces between adjacent slats of the body-forming means being 5 aligned, and, before the glue has set, binding the stacked assemblies closely together into a bundle by passing at least two tie-means thru said sets of spaces and completely around the set of cleats at each end, and firmly securing the tie-means to hold the members of each assembly tightly together during the setting of the glue and at the same time to bind the associated assemblies in a bundle for handling or shipment.
